UNITED STATES PATENT OFFICE.

ROBERT E. L. HOLMES, OF PHILADELPHIA, PENNSYLVANIA, AND CHARLES W. HOLMES, OF NEW YORK, N. Y., ASSIGNEES TO KEYSTONE DRILLER COMPANY, OF BEAVER FALLS, PENNSYLVANIA, A CORPORATION OF PENNSYLVANIA.

SUCKER ROD.

1,406,017.

Specification of Letters Patent. Patented Feb. 7, 1922.

Application filed March 22, 1921. Serial No. 454,506.

To all whom it may concern:

Be it known that we, ROBERT E. L. HOLMES and CHARLES W. HOLMES, citizens of the United States, residing, respectively, at 5 Philadelphia, in the county of Philadelphia and State of Pennsylvania, and New York, in the county of New York and State of New York, have invented a new and useful Sucker Rod, of which the following is a 10 specification.

This invention has reference to sucker rods and is intended particularly for use in deep well pumps of the reciprocating double piston type.

15 The invention relates more particularly to the sucker rods of double sucker rods wherein one pump piston is carried by a solid rod and the other piston is carried by a hollow rod through which the solid 20 rod extends.

It is the object of the invention to so construct the piston rods as to utilize resiliency or elasticity of the metal to relieve the shock due to the closing of the valves 25 when each plunger starts on its up stroke. To do this, the cross section at the joints on both the inside and outside rods is so increased that the desirable resiliency is obtained by placing a comparatively heavy 30 load on a given cross section of the center portion of the rods without straining the joints. Of course, the same result may be obtained by reducing the cross sectional area of the center and outer rod except at the 35 joints to take advantage of the resiliency of the metal without straining or crystallizing the joints.

In accordance with the invention, the rod ends are upset lengthwise, either actually 40 or effectively, and the meeting ends of the rods are united by couplings with the meeting ends of the hollow rods provided each with an internal circumferential groove, whereby a certain elasticity or springiness 45 is imparted to the rod. The groove so produced has a further function in providing in the hollow rod a lubricant container, whereby the movement of one rod with respect to the other distributes the lubricant on the inner surface of the hollow rod 50 and on the outer surface of the solid rod, thereby avoiding the effects of wear.

The invention will be best understood from a consideration of the following de-

tailed description taken in connection with 55 the accompanying drawing, forming part of this specification, with the understanding, however, that the invention is not confined to any strict conformity with the showing of the drawing but may be changed and 60 modified so long as such changes and modifications mark no material departure from the salient features of the invention as expressed in the appended claims.

In the drawing:

Fig. 1 is a longitudinal section, partly in elevation, of a pump cylinder, pistons and hollow and solid piston rods.

Fig. 2 is a longitudinal section through a joint of the hollow and solid rods on a 70 larger scale than Fig. 1 and removed from the pump casing.

Referring to the drawings, there is shown a pump casing 1 to which is connected a pump barrel 2, and the latter is shown as 75 provided with a bushing or connection 3, to receive a pump strainer. Within the pump barrel 2 are lodged two pistons 4, 5 respectively of the type employed in deep wells. These pistons are of the reciprocating form and are each provided with valves which, however, are not particularly shown in the drawings, for the valves in themselves, or even the specific structure of the piston, is not shown in the drawing.

80 The piston 4 is carried in the pump barrel 2 at the lower end of a hollow pump rod 6, while the piston 5 is carried at the lower end of a solid pump rod 7 below the piston 4 and the disposition of the pistons and the rods is such that the pistons are reciprocated in opposition, so that, as is customary in such pumps, the two pistons 90 propel a continuous stream of water from the well.

95 The hollow pump rod 6 is composed of numerous sections joined end to end, the number of sections depending upon the depth of the well and the solid pump rod is likewise composed of numerous sections joined end to end. Each section of the pump rod 6 has longitudinally upset ends 8, each with a tapered outer threaded surface 9 and these threaded ends are joined together by a coupling sleeve 10 provided with inner tapered screw-threads 11. The solid rods 7 is 100 connected together at the meeting ends of the sections by coupling sleeves 12, and in-

termediate of the coupled ends the solid rod is customarily of square shape, as shown at 13. The interior of each section of the hollow rod 6 has, for the greater portion of its 5 length, a bore 14 of greater diameter than the terminal portions of the bore indicated at 15 and occupying the upset ends 8 of the hollow rod. Where that portion of the hollow rod of larger bore, as indicated at 14, 10 approaches the upset portion 8, that is, the portion of smaller bore, there is an interior circumferential groove 16 deeper than the walls of the hollow rod so as to lodge and carry a certain amount of lubricant, serving 15 to lubricate the inner wall of the hollow tube and the outer wall of the solid rod.

By reducing the internal bore of the hollow rod at the joints, a wearing surface is 20 presented to the solid rod, thereby preventing, to some extent, the solid rod from wearing holes in the hollow rod, this being one of the primary advantages of using the upset ends of the hollow rod. Furthermore, this produces a thickening of the metal at 25 the point where friction occurs on the outside rod and the added thickness thereby caused in the walls of the hollow rod materially prolonging the life of such outside or hollow rod.

30 What is claimed is:—

1. A pump rod assembly for double piston deep well pumps, comprising hollow and solid reciprocatory pump rods, with each rod provided with joints between the meeting 35 ends of the respective sections and the rod sections adjacent to the joints being rendered elastic or resilient longitudinally to neutralize the shock due to the closing of the valves on the up strokes of the rods.

40 2. A pump rod assembly for double reciprocatory piston pumps, provided with joints between the meeting ends of the respective sections and the rod sections adja-

cent to the joints being rendered elastic or resilient longitudinally by producing circumferential channels in their walls, thereby reducing the thickness of the metal at 45 such points.

3. A pump rod assembly, comprising hollow and solid concentric reciprocatory 50 pump rods and pistons to correspond with joints at the meetings ends of the respective sections, and said rod sections adjacent the joints being upset and then reduced in thickness in circumscribed zones to neutralize the shock due to the closing of the valves 55 on the up strokes of the rods.

4. A pump rod assembly for double piston deep well pumps, comprising concentric hollow and solid pump rods reciprocable in 60 alternation and the outer rod having its sections provided with enlarged couplings interiorly reduced in circumscribed circumferential zones, whereby to there reduce the cross sectional area and increase the elastic 65 or resilient characteristic of the rod and thus tend to neutralize the shock to the rod and valves due to the closing of the latter on the up strokes of the rods.

5. A pump rod assembly for double piston deep well pumps, comprising concentric hollow and solid pump rods with joints 70 at the meeting ends of the respective sections, with the ends of the hollow sections where connected together reduced in internal diameter and increased in external diameter whereby there is added thickness and a localization of wear due to friction between the two rods and a corresponding prolongation of the life of the outside or 75 hollow rod.

In testimony that we claim the foregoing as our own, we have hereto affixed our signatures.

ROBERT E. L. HOLMES.
CHARLES W. HOLMES.
